UNITED STATES PATENT OFFICE

164,398

TOY PROPELLER-EJECTING GUN

Joseph B. Barricks, Des Moines, Iowa

Application May 17, 1951, Serial No. 15,226

Term of patent 14 years

(Cl. D34—15)

To all whom it may concern:

Be it known that I, Joseph B. Barricks, a citizen of the United States and a resident of Des Moines, county of Polk, and State of Iowa, have invented a new, original, and ornamental Design for a Toy Propeller-Ejecting Gun, of which the following is a specification, reference being had to the accompanying drawing, forming part hereof, in which:

Fig. 1 is a side elevational view of a toy propeller-ejecting gun showing my new design;

Fig. 2 is a top plan view;

Fig. 3 is a bottom plan view;

Fig. 4 is a front view looking toward the right in Fig. 1; and

Fig. 5 is a rear view of my new design looking toward the left in Fig. 1.

I claim:

The ornamental design for a toy propeller-ejecting gun, substantially as shown.

JOSEPH B. BARRICKS.
